(57) **CLAIM**

The ornamental design for a mousetrap, as shown and described.

DESCRIPTION

FIG. 1 is a perspective view of a mousetrap, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken line showing of portions of the mousetrap is included for the purpose of illustrating only and forms no part of the claimed design.
